Ernest G. Goodwin, Pelham, N. Y., assignor to
 Standard Coupler Company, New York, N. Y.,
 a corporation of New Jersey

Application March 5, 1931, Serial No. 520,368

29 Claims. (Cl. 105—193)

This invention relates to snubbers and has for its principal object the provision of a more efficient snubbing device for a railway bolster to limit the rocking and vertical jiggling of a car 5 and to eliminate entirely the accumulative rolling.

An important object of the invention is to provide for lateral motion of the bolster without in any way lessening the snubbing effect and this 10 object is secured by providing a spring seat in one or more pieces between the truck springs and the snubbing shoes. Incidental to the use of a single spring plate a feature of the invention is the provision of convex roller engaging faces 15 in place of the usual plane faces which have been heretofore used.

A very important feature of the present invention is the provision of liner retaining means especially the provision of means for preventing 20 this channel-shaped member from spreading or separating its two flanged ends which might cause it to come out of engagement with its retaining shoulders. Such construction eliminates the usual rivets which are quite unsatisfactory 25 when they have countersunk heads as is customary in this field.

A still further object of the present invention is the provision of supporting the bolster directly from the springs on the plank as well as indirectly supporting this same member by other 30 springs which directly engage the snubbing shoes, the result being that the shoes can have the proper angle and at the same time the bolster will have sufficient metal and, more important still, 35 can have its full depth and consequently a considerably greater bending moment.

Other objects of the invention will be apparent from the following description and cover more particularly specific improvements in definite 40 members such as the rollers and rockers and also the provision of means for eliminating the sudden depression of one side of the truck springs as upon a sudden move forward or a quick stop, this latter provision being met by permitting contact 45 between the bolster and the side frame under such circumstances while allowing no direct contact whatsoever between them during normal running.

In my previous application, Serial No. 356,253, 50 filed April 18, 1929, entitled Bolster damper, I have gone rather fully into the discussion of the tendency of railway cars to rock excessively whether they are loaded or not and to the danger of such side to side rolling or rocking of the car becoming 55 accumulative to a point where the springs might

easily be brought solid with a consequent injury to the spring or to some other part of the truck, and in some respects the present application may be considered as improving the device illustrated in my earlier application just mentioned, as for example, adapting the earlier device so that lateral motion may be included in view of the fact that a large number of our railroads now use devices of this type and it is therefore advisable to provide snubbing action 10 coupled with lateral motion mechanisms.

In my earlier device I have shown the liner held to the column of the side frame or to the bolster by means of rivets having countersunk heads altho I have also suggested in the earlier 15 application the use of shoulders for limiting the up and down movement of the liner. I find, however, in actual practice that the countersunk rivets have a life altogether too short and the rivets fail between their two heads. In the present structure I have therefore substituted for the rivets or holding means a continuous U-shaped shoulder at top and bottom and have prevented any spreading of the channel-shaped liner by providing upper and lower lips at either side into 20 which the liner may readily slide and have thus eliminated a need for the rivets altho I prefer to retain some sort of holding means, for example, a loose bolt which keeps the liner in place when not frictionally engaged and also in the emergency case where a worn standard bolster is used 25 in connection with the side frame illustrated.

In the drawings:

Figure 1 is a side elevation partly in central section.

Figure 2 at the left is a section thru the column looking down upon the bolster and at the right is a half section just below the upper plate of the bolster, see line 2—2 of Figure 1.

Figures 3 and 4 are each vertical sections thru the rocker members on line 3—3 of Figure 1, one showing a single roller, the other showing a plurality of "biscuits".

Figure 5 is a side elevation partly in section showing a modified form in which a single spring 45 plate is used in place of the two separate plates illustrated in Figure 1.

Figure 6 is a vertical section taken on line 6—6 of Figure 1 to one side of the rocker elements primarily illustrating the tongue and groove arrangement between the bolster and the shoe.

Figure 7 is a top plan view of one of the shoes.

Figure 8 is a side elevation of the bolster end.

Figure 9 is a cross section taken longitudinally of the bolster on line 9—9 of Figure 8.

Figure 10 is a view similar to Figure 1 showing the preferred form of my invention as applied to the larger trucks.

Figure 11 is a view similar to Figure 2 but showing the truck of Figure 10.

Referring particularly to Figure 1, 10 is a truck side frame of usual design save that it is recessed on each of the two opposed vertical faces to form an upper shoulder 11 and a lower shoulder 12 between which is placed the replaceable wear plate 14 commonly called the liner and which is held in place, when not engaged, by a bolt 16 passing thru a slotted hole 17 in the two walls of the column. The bolt is not actually necessary altho highly desirable when a standard bolster is substituted for the bolster hereinafter described, which will only be the case in emergencies, but where a standard bolster is used and is badly worn or otherwise does not fill the space from column to column some provision should be had for retaining the two liners in place.

Under ordinary circumstances the liners are held in place most effectively by the two three-sided shoulders particularly when lips like 18 are provided each of which engages a corner of the side flange of the channel-shaped liner. Without these lips 18 there is a tendency for the liner to straighten, that is, for the two flange edges to work away from parallelism and this tendency is entirely overcome by the provision of the lips 18 which, somewhat snugly engage the liners but not to such an extent as to make it difficult to slide the channel-shaped liners in place or to remove them readily when worn. Except for details later to be described as well as the lips and the shoulders, the side frame follows standard practice and may receive standard equipment.

The bolster ends, as in my previous device, have sloping faces extending upwardly and outwardly from the center line and may directly engage the shoes with an outwardly wedging action but it is highly preferable that instead of direct frictional engagement there shall be a rolling engagement such as is provided by the rockers 20 which may be rollers as at 20^a in Figure 3 or may be rocker blocks as at 20^b in Figure 4. In either case the vertical longitudinal cross section of the rocker shall be as shown in Figure 1, the rod 20^a being elliptical in transverse cross section while the rockers 20^b may either be highly oblate spheroids or they may be blocks, square in horizontal cross section and elliptical in both longitudinal and transverse sections.

When these rockers are rods no lateral movement of the bolster is permitted but where they are biscuits, as in Figure 4, both functions are present, that is, the lateral movement of the bolster is permitted while retaining all of advantages of the rocker rod which cams the shoes outward.

The truck spring units 22 are four in number as illustrated in the truck of Figures 1 to 7 and are six in number in the truck illustrated in Figures 10 and 11. Quite obviously the springs may engage either single spring seats as in Figure 1, the bolster itself, or any combination, for example, in Figure 10 a lateral pair of spring units 22 engage each of the two shoes while the central pair of springs 23 directly engage the spring plank, not shown, and the bolster.

For the sake of simplicity the device of Figures 10 and 11 will now be considered as in these figures I have purposely omitted the lateral move-

ment device which can readily be added as illustrated in Figures 3 and 4 but which naturally is not at all essential. The bolster has the usual top plate 25 and has two downwardly and inwardly directed lower plates 26, the angles being such that a substantially wide lower surface 27 is provided which forms a spring seat for one or more spring units 23.

The lower sloping faces 28 may directly engage the parallel faces 29 on the shoes but all the advantage of such construction is obtained without the accompanying disadvantages by grooving a small central portion of the shoe to form a plane surface 30 on which the rocker rods or biscuits 20 roll and in providing a concave surface 31 on the sloping lower faces of the bolster. The reinforcing rib 32 of the bolster is quite novel, rising normal to the surface 28 so that pressure to or from the rocker will be carried directly to the top plate of the bolster in the line of stress or pressure. The rib 32 extends to the side bearing seat 33 and strengthens the bolster at this point as well.

The shoe 35 is shown in top plan view in Figure 7 and in side elevation and cross section in Figures 1 and 10. This member is an integral piece and consists of a channel-shaped plate which includes the main friction member 36 and two side flanges 37. The member 36 at all times and the flanges 37 under certain circumstances frictionally engage the liner 14 producing the resistance necessary to dampen the action of the vertical movement of the bolster. The lower plate 38 of each shoe is generally horizontal and rests upon the spring 22 preferably carrying an elliptical spring boss 39 to center the spring nest unit, being elliptical rather than circular because upon wear of the shoe this member will move outwardly toward the liners whereas it is highly undesirable that the axis of the spring 22 shall follow. By having the boss elliptical this outward wear is taken care of without any tendency to slope the axis of the spring.

Centrally and longitudinally of the shoe is a tongue 40 interrupted at its middle by the groove 41 which provides the plane rocker engaging surface 30 and corresponding to the tongue 40 is the groove 42 on the bolster bounded by downwardly extending ribs 43 which may at times engage the tongue 40 to limit lateral movement of the bolster. The bolster automatically centers itself by virtue of the action of the rocker biscuits when they are used and by the normal action of the Barber rollers 44 in the customary and well known manner. The tongue and groove arrangement is not essential as obviously the result can be obtained by engagement of the shoe with the portion 45, 46 and 55 of the bolster as well as by contact between the bolster, the shoe and the side frame, in spite of which, however, I find the tongue and groove arrangement highly desirable under certain circumstances. It also serves to retain the rockers 20.

The form of bolster illustrated in Figure 10 is particularly desirable in the case of the larger cars in which the distance from column to column is increased to such an extent that when the shoes are designed to reach out far enough while keeping the proper angle, the bolster is necessarily shortened in depth and for this reason it is advantageous to preserve the angle of the shoe while shortening its column to column length thus permitting the bolster to engage some of the springs directly. By this construction the central portion of the bolster is greatly strengthened for

being the full depth it has a considerably greater bending moment than if it should be necessary to reduce the depth to permit the shoes to engage all of the springs.

5 In so constructing the device I find it highly advisable to design the parts so that initially the spring receiving bottom face of the shoe shall be somewhat appreciably lower than the parallel similarly acting face 27 of the bolster. It is quite 10 natural that the shoes, as they become worn, will move upwardly as well as outwardly on account of the inclination of the roller face and should we start with all of the spring engaging faces parallel we would obviously have, after a period of 15 wear, a central set of springs which would be loaded somewhat greater than the outside springs of the set. By designing the parts as illustrated while we will start with the springs at the sides loaded to a slightly greater extent than the 20 middle springs the loading will be entirely uniform after a considerable amount of wear and from this point on to replacement the loading of the outer springs will be only a slight amount less than the center springs.

25 Referring particularly now to Figure 11, the side frame column 48 is provided with an extended flange 49 which comes into use only upon sudden starting or stopping of the car at which time this lug engages a stop lug 50 on the bolster 30 to check the tendency of the bolster to move longitudinally of the car with reference to the side frames as, for example, in the case of a sudden application of the brakes, or by a sudden bumping backward of the car in front. In all other 35 similar devices with which I am familiar any such movement of the bolster would depress the spring in the direction of the movement continuing until the slack between the bolster and the engaging part is taken up. Since the slack increases as the wear increases this tendency is 40 objectionable and is limited by the provision of these two lugs which are not intended to contact except momentarily under the conditions outlined and hence the wear on the two lugs is 45 negligible.

Referring now particularly to the right hand side of Figure 2, it will be noted that the side frame column 48 is snugly engaged on all three sides by the liner 14 but that there is a space 50 53 between the liner and the shoe and there is likewise a space 54 between the shoe and the inward flange 55 on the bolster which flange is considerably longer in fore and aft direction than is the corresponding flange 56. The purposes of 55 these features is to provide smoothness of action and convenience of assembly, the space 54 giving clearance so that the bolster can have lateral movement on the rockers 20^a if they are used. If the rods 20^a are used in place of the biscuits 60 20^b this clearance 54 is not needed. The clearance 53, however, is needed in each case where the Barber rollers 44 are employed. The shortening of the rib 56 with respect to the rib 55 makes convenient the removal of the side frame. If 65 the rib 56 were of the same extent as the inner rib 55 it would be necessary to tear the truck apart, requiring the removal of the spring plank. With the construction shown, however, the springs are removed, the shoes lowered and then 70 the side frame can be drawn directly off the journals.

In connection with the Barber rollers 44, each of which is a cylindrical rod seated in an elliptical cavity making the device self-centering, I prefer that these rollers remain cylindrical as shown

in all of the figures. Where I use two spring seats 60, as in Figure 1, I have no difficulty because the springs can move independently but where, as in Figure 5, I form the spring seat 61 as a single piece it is highly desirable to prevent the biting 5 of the edge of the rollers 44 as would occur if one shoe were at a higher level than the other. Consequently to prevent undue wear or damage to the edges of the rollers I make one or both of the roller engaging surfaces 63 convex which permits me to retain the cylindrical rollers; otherwise I would be forced to use rollers of elliptical, longitudinal or axial, cross section.

10 In Figure 4 the rocker biscuits, whether square or circular in plan, have the same function, that is, in addition to the normal action which is given by the roller rods 20^a these biscuits with the Barber rollers 44 give a double lateral motion one portion of which is snubbed by the friction against the column while the other, that is, the bearing between the bolster and the friction shoes, is not snubbed. However, the lateral movement of the bolster is increased over the amount which would be given by the rocker biscuits alone or by the lateral-movement-permitting rollers 44.

15 What I claim is:

1. In a device of the character described, a frame, a bolster, a plurality of springs for supporting said bolster upon said frame, and means 30 positioned between said bolster and some of said supporting springs for engaging the bolster and slidably engaging said frame for dampening vertical and lateral movement of the bolster in the 35 frame.

2. In a device of the character described, a side frame having two vertical faces, a shoe engaging each face, a bolster resting upon the two shoes, said bolster and shoes being relatively movable in response to variation of pressure on the bolster, 40 and means for allowing lateral movement of the bolster and the shoes with respect to the side frame.

3. A strut channel-shaped in cross section, connecting the tension and compression members 45 of a side frame, an upper ledge or shoulder and a lower ledge or shoulder on the three sides of said strut adapted to snugly receive a channel-shaped liner, and lugs extending from said ledges at each end to receive the corner of said liner to prevent 50 the spreading of the liner when in use.

4. The combination of a bolster member, a frame receiving said bolster member, a shoe member frictionally engaging the frame and supporting the bolster member, means for facilitating lateral movement of the bolster member, and means limiting relative lateral movement of the bolster member and the shoe member, said last mentioned means including a longitudinal groove in one of the members and a longitudinal tongue 60 in the other of the members and fitting loosely within said groove.

5. A shoe having a vertical friction face to engage a column wall, a horizontal plate forming the bottom of the shoe, a sloping plate connecting the bottom plate and the side plate, said sloping plate having a lateral groove therein to serve as a roller engaging face and having a tongue extending upwardly from said sloping plate at right angles to the roller groove, said 65 tongue being adapted to cooperate with a groove in a bolster to limit lateral movement of the bolster and also to limit movement of a roller on the roller face of the shoe.

6. A horizontal force cushioning member for 75

- use between a bolster and a shoe, consisting of a biscuit shaped member elliptical in vertical longitudinal section and also in vertical transverse section.
- 5 7. In combination, a bolster and a shoe each having rocker receiving sloping faces and rockers engaging said faces with rolling contact, said rockers being elliptical in longitudinal cross section.
- 10 8. The device of claim 7 in which the rocker engaging face of the shoe is plane and the rocker engaging face of the bolster is curved.
9. In a snubbing device, a side frame having parallel vertical faces, a pair of shoes each engaging one of said faces, a plurality of springs, a bolster supported upon one or more of said springs and indirectly supported thru the shoes upon the other springs.
- 15 10. In a snubbing device, a side frame, a pair of shoes each engaging said side frame with frictional contact, a truck spring beneath each shoe, a bolster above said shoes and having a central portion extending between the shoes, a truck spring directly engaging the central portion of the bolster, and means between the bolster and each shoe for urging the shoe outwardly against the side frame as the bolster moves down to compress the springs.
- 20 11. In a device of the character described, a side frame having a pair of channel-shaped struts, a pair of shoes each frictionally engaging the web of the channel of the column and loosely engaging the sides of the column, a bolster resting upon the shoes, said shoes tending to move with respect to the bolster in response to varying vertical forces on the bolster and shoes, a spring seat below each shoe and snugly engaging the column on both web and side flanges and rollers between the spring seats and the shoes.
- 25 40 12. In a device of the character described, a side frame, a pair of shoes each engaging a column of the side frame, a bolster resting upon the shoes, a spring seat below the shoes and engaging both columns, rollers between the spring seat and the shoes, the roller engaged face of each shoe being convex in longitudinal section thru the axis of the roller whereby to avoid damage to the end of the roller as one shoe moves with respect to the other.
- 30 45 50 13. In a device of the character described, a side frame having two columns channel-shaped in horizontal section, a bolster, truck springs supporting the bolster between the columns of the side frame, stop lugs on the bolster and on the columns adapted to contact when the bolster moves longitudinally of the side frames as in the case of sudden application of brakes or jerks received thru the coupler, said lugs being out of contact with each other in normal operation of the car.
- 55 60 65 70 75 14. In combination, a bolster and a bolster shoe having opposed slanting faces, an elongated body between and having rolling engagement with said faces, each face having a smooth surface which is engaged by the body, and interlocking ribs rising from said opposed faces and normal to the axis of said body, some of said ribs being located to engage the lower side of said body for positioning the same during the assembling together of the bolster, bolster shoe and body.
15. In combination, a pair of truck spring seats, a shoe upon each seat and having a vertical friction face and a sloping upper face, a bolster end upon the two shoes and having two sloping faces parallel respectively to the adjacent upper faces of the shoes, and rolling bodies between the bolster and the shoes and between the shoe and the seats.
16. In a snubbing device, a side frame having opposed vertical faces, a pair of vertically movable shoes each engaging the respective face, a plurality of springs, a bolster supported from one or more of said springs, said shoes being supported by the other springs and partly supporting the bolster.
17. In a snubbing device, a side frame having substantially parallel faces, a pair of shoes each engaging one of said faces with sliding frictional contact, a plurality of springs having their axes substantially vertical, a bolster supported by one or more of said springs and additionally supported thru said shoes, upon the other springs, said bolster and shoes having relative movement to provide compensation for slight non-parallelism between said faces and thereby to avoid undue increase or decrease in pressure of said sliding frictional contact with vertical movement of the bolster.
18. In a snubbing device, a side frame having parallel opposed friction faces, a pair of shoes each slidingly engaging one of said faces with friction contact, a plurality of supporting springs, a bolster supported directly from one or more of said springs and indirectly supported thru the shoes upon the other springs, said shoes being movable vertically with the bolster and also being movable horizontally with respect to the bolster, such horizontal movement of the shoes providing compensation for the wearing away of the parallel friction faces and the shoes during service and also permitting the increase and decrease of the friction contact with the increase and decrease of load on the bolster.
19. In a snubbing device, a side frame having opposed vertical friction faces, a pair of shoes each having a vertical portion engaging one of said vertical faces and also having a sloping side, a plurality of supporting springs, a bolster supported from one or more of said springs, said shoes being supported by the other springs and partly supporting the bolster, and members each having a curved face engaging said bolster and resting upon the sloping side of the adjacent shoe.
20. In a snubbing device, a side frame having friction faces, a snubbing shoe frictionally engaging one of said faces, a bolster, and a plurality of springs carried by the side frame, one or more of said springs supporting the bolster end from beneath and others of said springs supporting the shoe from beneath and through the shoe indirectly supporting the bolster.
21. In a device of the character described, a side frame having two vertical faces, a shoe engaging each face, bolster springs, snubbing springs, a bolster supported by all of said springs for vertical movement in said frame, means between said bolster and the snubbing springs for transforming vertical forces acting on said bolster into diagonal and horizontal components, said horizontal components being in a direction to thrust the shoes against said faces, and said shoes being movable on said faces in proportion to the vertical movement of the bolster whereby snubbing occurs in proportion to the vertical displacement of the bolster.
22. In combination, a bolster member and a shoe member having opposed slanting faces, an elongated rolling body between said members, each of said faces having a smooth surface which

surfaces are engaged by the rolling body, and interlocking ribs rising from said opposed faces and normal to the axis of said rolling body for positioning the rolling body during both assembling together of the members and body and in operation.

23. In a car truck, side frames having bolster openings, a bolster structure having ends disposed within said bolster openings, bolster springs supporting the ends of said bolster structure from said side frames, pairs of contacting members interposed between said bolster structure and portions of said side frames, one member of each of said pairs being a wedge member, each end of said bolster structure resting on one member of each pair and springs interposed between the wedge member of each pair and portions of said side frames, said last mentioned springs urging said wedge members into tighter wedging relation as said bolster springs are increasingly compressed.

24. In a car truck, side frames having bolster openings, a truck bolster structure having ends disposed within said openings, bolster springs supporting the ends of said bolster structure from said side frames, relatively movable inner and outer contacting members interposed between the ends of said bolster structure and portions of said side frame, said bolster structure resting on and movable with respect to said inner members and vertically disposed springs between said outer members and other portions of said side frames, said outer members being wedges, said last mentioned springs urging said wedges into tighter wedging relation as said bolster springs are increasingly compressed.

25. In a car truck, side frames having bolster openings, a truck bolster structure having ends disposed within said openings, bolster springs supporting the ends of said bolster structure from said side frames, said side frames having surfaces spaced from the sides of the ends of said bolster structure, relatively movable inner and outer contacting members interposed between said bolster and said spaced surfaces, said inner members being movable on the bolster, said outer members being wedges, said side frames having

spring supports below said wedges, and springs resting on said spring supports and bearing at their upper ends against said wedges.

26. In a device of the character described, a side frame having two snubbing faces, a bolster end spring supported for vertical movement between said faces, vertical movement dampening means comprising a shoe frictionally engaging one of said faces and wedging means separately spring supported between the shoe and the bolster end for urging said shoe against the proximate face and simultaneously urging the bolster end toward the other face.

27. In combination, a side frame having spaced columns, a bolster having an end vertically and horizontally movable between the columns, spring means carried by the side frame and supporting said end of the bolster, and a snubbing device cooperating with the columns to dampen the vertical movement of the bolster, said snubbing device including a lateral motion mechanism operative to cause the device to dampen the lateral movement of the bolster.

28. In combination, a side frame having spaced columns, a bolster having an end vertically and horizontally movable between the columns, a spring means carried by the side frame and supporting said end of the bolster and a snubbing device cooperating with the columns and springs to dampen the vertical movement of the bolster, said snubbing device including lateral motion mechanism to dampen the lateral movement as the bolster moves from side to side, said mechanism comprising rolling members upon which the bolster end directly rests.

29. A strut channel-shaped in cross section, connecting the tension and compression members of a side frame, an upper ledge or shoulder and a lower ledge or shoulder on the three sides of said strut adapted to snugly receive a channel-shaped liner, lugs extending from said ledges to overlie portions of the margin of said liner and securing means passing thru the strut and liner and cooperating with said lugs to prevent the spreading of the liner when in use.

ERNEST G. GOODWIN.
